(57) CLAIM

The ornamental design for a portion of a refrigerator display case, as shown and described.

DESCRIPTION

FIG. 1 is a perspective view of a portion of a refrigerator display case embodying my new design;

FIG. 2 is a front view of FIG. 1;

FIG. 3 is a side view of FIG. 1; and,

FIG. 4 is an enlarged top view of FIG. 1.

The broken line showing of the environment is for illustrative purposes only and forms no part of the claimed design. The broken lines which define the boundaries of the claimed design form no part thereof.

1 Claim, 4 Drawing Sheets

FIG. 2

FIG. 4

UNITED STATES PATENT AND TRADEMARK OFFICE
CERTIFICATE OF CORRECTION

PATENT NO. : Des. 571,380 S
APPLICATION NO. : 29/223693
DATED : June 17, 2008
INVENTOR(S) : Jesus Ugarte

Page 1 of 1

It is certified that error appears in the above-identified patent and that said Letters Patent is hereby corrected as shown below:

In the title item [54]:

replace “REFRIGERATOR” with --REFRIGERATED--

In the Description line 1:

for FIG 1: replace “refrigerator” with --refrigerated--

In the Claim line 2:

replace “refrigerator” with --refrigerated--

Signed and Sealed this

Second Day of September, 2008
